ROTATING DISPLAY SIGN

Murray D. Harris, Murrayville, British Columbia, Canada

Application October 6, 1952, Serial No. 313,313

4 Claims. (Cl. 40—130)

This invention relates to a rotating display sign capable of producing a wide variety of visual effects.

An object of the present invention is the provision of a display sign having at least two concentric rotors capable of rotating in opposite directions and which are capable of producing unique effects.

At present, a great deal of effort is being used to produce display or advertising signs having moving or rotating elements. In most cases, the effect is only partially successful since the apparent movement is obtained by illusion.

The display sign according to this invention may be used by itself, or it may be incorporated into a larger sign. In either case, the present device includes two concentric rotors and means for rotating them in opposite directions. Each rotor is provided with illuminating means which may be in the form of a plurality of light bulbs, neon tubes or other lighting equipment. The illuminating means may include any colour or combination of colours to produce a desired effect. It has been found that when the rotors are moving in opposite directions, lights of certain colours produce colour effects which are entirely different from the original colours.

An example of this invention is illustrated in the accompanying drawings, in which,

Figure 1 is a front elevation of the rotating display sign,

Figure 2 is a plan view of the sign,

Figure 3 is an enlarged longitudinal view through the sign,

Figure 4 is a cross section taken on the line 4—4 of Figure 3,

Figure 5 is a cross section taken on the line 5—5 of Figure 3, and,

Figure 6 is a cross section taken on the line 6—6 of Figure 3.

Referring to the drawings, the display sign includes inner and outer rotors 10 and 11 which are concentrically arranged, as clearly shown in Figures 1 and 3. The rotors 10 and 11 are provided with display surfaces or plates 12 and 13, respectively, facing in the same direction. Each of these plates carries suitable independent illuminating means. As it may be desirable to alter the visual effect of the sign by changing the illuminating means or the design thereof, plates 12 and 13 may be removably mounted in their respective rotors in any convenient manner, such as by means of screws 16 and 17, see Figure 3. In the illustrated example, the illuminating means of rotor 10 consists of a plurality of light bulbs 19 projecting outwardly from the plate 12, while that of the outer rotor consists of a plurality of light bulbs 20 projecting outwardly from the plate 13. The sockets for these bulbs are preferably connected in parallel in the usual manner, and the wiring for these is covered by casings 22 and 23 in the inner and outer rotors.

An outer hollow shaft 28 is fixedly connected to the outer rotor 11 at 29 in any convenient manner. Suitable means is provided for rotatably supporting this shaft. In

this example, the shaft is journaled in spaced bearings 30 and 31 having supporting standards 32 and 33. Electrical conductors 34 and 35 extend from the wiring housing 23 of the outer rotor and through the shaft.

5 An inner hollow shaft 36 is connected to the inner rotor 10 at 37 in any desired manner and extends through the outer shaft and beyond the back end thereof. Suitable means is provided for rotatably supporting the inner shaft, and this may consist of ball bearings 38 and 39 carrying the inner shaft and spaced from the outer shaft by insulating rings 40 and 41. These rings are provided with holes through which conductors 34 and 35 extend. Figure 4 shows holes 42 and 43 in the ring 41 for this purpose.

15 Electrical conductors 45 and 46 extend from the wiring housing 22 in the inner rotor through the inner shaft 36.

The outer and inner shafts 28 and 36 may be rotated in opposite directions in any convenient way. For example, a single source of power may be connected thereto by suitable gearing or, as shown, the shafts may have pulleys 50 and 51 fixedly secured thereto and connected by belts 52 and 53 to separate motors 54 and 55. It is obvious that the shafts and their rotors may be turned in the same direction at different speeds, but it is preferable to rotate them in opposite directions.

20 A cylindrical housing 60 is aligned with and fixedly secured to the back end of the outer shaft 28. This housing includes a sleeve section 61 screwed to a main section 62, the latter being fixedly connected to the shaft.

25 The housing is provided with an opening 64 facing outwardly from the shaft, and a transverse insulating plate 65 is fitted in the main section of the housing inwardly from the open end thereof. This plate has a central hole 66 therein through which the inner shaft 36 extends. The conductors 34 and 35 from the outer rotor are connected to suitable contacts carried by the plate 64. In this example, these contacts are in the form of concentric rings 70 and 71 positioned on the outer surface of the plate. Conductor 34 is connected to ring 70, and conductor 35 is connected to ring 71.

30 As the housing 60 is rotating when the sign is in operation, it is necessary to provide means for supplying electricity to the conductors 34 and 35 in this rotating element. A stationary block 75 extends into the open end of the housing 60, said block having a reduced end 76 supported by a bearing 77 having a base 78. Carbon brushes 81 and 82 project outwardly from sockets 83 and 84 formed in the block 75. Springs 86 and 87 in these sockets press the brushes 81 and 82 against the contact rings 70 and 71 of the plate 65 in the housing 60. Electrical conductors 90 and 91 extend from the brushes 81 and 82 through the block extension 76 to a suitable source of electrical power, not shown.

35 A housing 95 similar to housing 60 is aligned with and is fixedly connected to the back end of shaft 36. This housing is provided with an insulating plate 96 carrying a contact ring 97 and another contact 98 centrally thereof to which the conductors 45 and 46 from the inner rotor are respectively connected. An insulating block 102 fits into the open end of housing 95 and has spring-loaded brushes 103 and 104 projecting therefrom and engaging the contacts 97 and 98. The block 102 has an extension 107 which is carried by a suitable bearing 108 having a base 109. Electrical conductors 111 and 112 extend from the brushes 103 and 104 through the bearing 108 to a suitable source of electrical power, not shown.

40 In operation, shafts 28 and 36 are normally rotated in opposite directions by the motors 54 and 55, and this turns the rotors 10 and 11 in opposite directions. Electrical power is supplied to the light bulbs 20 of the outer rotor by conductors 90 and 91, brushes 81 and 82, contact rings 70 and 71, and conductors 34 and 35. Simi-

3

larly, electrical power is supplied to the bulbs 19 of the inner rotor by conductors 111 and 112, brushes 103 and 104, contacts 97 and 98, and conductors 45 and 46. Thus electrical energy is supplied from a stationary source to the rotating elements without any difficulty. The rotation of the light bulbs of the rotors in opposite directions produces a very pleasing effect. This effect may be changed by altering the colours of the bulbs or by rearranging them in different designs. The removable display surfaces or plates 12 and 13 make it possible quickly and easily to change the illuminating designs of the rotors.

What I claim as my invention is:

1. A rotating display sign comprising concentrically arranged inner and outer rotors having inner and outer front display surfaces facing in the same direction and in a common plane, illuminating means mounted on each rotor at the display surface thereof independent of that of the other rotor, an outer hollow shaft connected to and extending rearwardly from the outer rotor, means for rotatably supporting the shaft, an inner hollow shaft connected to the inner rotor and extending through and beyond the outer shaft, power means for rotating said shafts relative to each other, and electrical conductors extending through the shafts for supplying current to the illuminating means of the rotors, whereby the lighting of the rotors rotating relative to each other blends to produce a novel effect.

2. A rotating display sign comprising concentrically arranged inner and outer rotors having inner and outer front display surfaces removably mounted thereon and facing in the same direction and in a common plane, illuminating means carried by the display surface of each rotor independent of that of the other rotor, an outer hollow shaft connected to and extending rearwardly from the outer rotor, means for rotatably supporting the shaft, and inner hollow shaft connected to the inner rotor and extending through and beyond the outer shaft, power means for rotating said shafts in opposite directions, electrical conductors extending from the illuminating means of each rotor through the shaft connected to the latter, and a brush arrangement at the back end of each shaft forming an electrical connection with the conductors in said shaft, whereby the lighting of the rotors rotating in opposite directions blends to produce a novel effect.

3. A rotating display sign comprising an outer annular rotor, an inner rotor within the outer rotor, a front display

surface on and facing outwardly from the inner rotor, an annular front display surface on and facing outwardly from the outer rotor, said display surfaces being in a common plane, illuminating means mounted on each rotor display surface independent of that of the other rotor, the illuminating means of the outer rotor surrounding and being spaced from the illuminating means of the inner rotor, an outer hollow shaft connected to and extending rearwardly from the outer rotor, means for rotatably supporting the shaft, an inner hollow shaft connected to the inner rotor and extending through and beyond the outer shaft, power means for rotating said shafts relative to each other, and electrical conductors extending through the shafts for supplying current to the illuminating means of the rotors, whereby the lighting of the rotors rotating relative to each other blends to produce a novel effect.

4. A rotating display sign comprising an outer annular rotor, an inner rotor within the outer rotor, a front display surface removably mounted on and facing forwardly from the inner rotor, an annular front display surface removably mounted on and facing forwardly from the outer rotor, said display surfaces being in a common plane, illuminating means mounted on each rotor display surface independent of that of the other rotor, the illuminating means of the outer rotor surrounding and being spaced from the illuminating means of the inner rotor, an outer hollow shaft connected to the outer rotor centrally thereof and extending rearwardly therefrom, an inner hollow shaft connected to the inner rotor centrally thereof and extending rearwardly therefrom through and beyond the outer shaft, power means for rotating said shafts relative to each other, and electrical conductors extending through the shafts for supplying current to the illuminating means of the rotors, whereby the lighting of the rotors rotating relative to each other blends to produce a novel effect.
